(57) **CLAIM**

The ornamental design for lamp as shown and described.

DESCRIPTION

7. Lamp
7.1 : Back
7.2 : Bottom
7.3 : Front
7.4 : Front view alternative position
7.5 : Left
7.6 : Left view alternative position
7.7 : Perspective

The top view is omitted because this part is not visible in use due to the mounting of the lamp in the ceiling. The broken lines in the figures are illustrative of supporting structure of the lamp and form no part of the claimed design. The right side view is omitted because it is a mirror image of the left side view.
